UNITED STATES PATENT OFFICE.

ALBERT L. AUSTIN, OF CLEVELAND, OHIO.

RECTAL DILATOR AND IRRIGATOR.

Application filed April 4, 1921. Serial No. 458,415.

To all whom it may concern:

Be it known that I, ALBERT L. AUSTIN, a citizen of the United States, residing at Cleveland, in the county of Cuyahoga and State of Ohio, have invented certain new and useful Improvements in Rectal Dilators and Irrigators, of which the following is a specification.

My invention relates to improvements in rectal dilators and irrigators, the present embodiment of the invention being particularly designed and adapted for use in the treatment of rectal diseases and disorders.

The primary object of the invention is to provide a generally improved instrument or appliance of the character indicated which will be exceedingly simple in construction, cheap of manufacture and efficient in use.

A further and very important object of the invention is to provide an instrument which will not only dilate the walls of the rectum but one in which the inlet and outlet ports are so arranged relative to each other as to provide for an improved circulation of the cleansing or treating liquid within the adjacent walls of the parts being treated as well as one in which the danger of the ports becoming clogged will be reduced to a minimum.

A still further object is the provision of an improved irrigating member adapted to be readily inserted in or removed from the dilator body, said irrigating member being of standard form and adapted to be used interchangeably with dilator members or bodies of varying sizes and dimensions.

A still further object is the provision of an improved tubular irrigating member provided with a removable plug or filler adapted to close the irrigating member and form the tip or nose of the dilator head when inserted and to be removed therefrom to form a centrally located return port or opening for the cleansing and treating liquid when used as an irrigating device after initial dilation of the parts, said central irrigating member, however, forming an inlet port or opening for the introduction of treating salve or ointment by the initial application of the latter at the base of the tubular irrigating member and the passage of such salves or ointments upwardly through the port of the irrigating member through the medium of the removable plug or insert acting as the carrier or plunger to finally emit such salves or treating ointments at the

top or apex portion of the dilator head where such treating mediums will be permitted to pass outwardly and downwardly over the dilator head and into contact with the walls of the adjacent parts to be treated.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the accompanying drawings, forming a part of this specification, Figure 1, is a top plan view of the improved irrigating rectal dilator with the parts assembled preparatory to insertion and use as a dilator.

Fig. 2, a side elevation of the same partly in section.

Fig. 3, a side elevation of the interchangeable tubular irrigating member and removable plug or filler, detached.

Fig. 4, a cross-sectional view, taken on line 4—4 of Fig. 5, and illustrating in particular the arrangement of the port openings in the nozzle head.

Fig. 6, a side elevation of the removable plug or insert removed from the removable tubular irrigating member.

Fig. 7, a side elevation, partly in section, of a dilator body in different form and showing particularly how the central tubular irrigating member may be used therein as well as in dilator bodies of various sizes and forms.

Similar numerals of reference designate like parts throughout all the figures of the drawings.

The improved dilator and irrigator comprises a hollow dilator body which may be of any suitable and convenient form, but is preferably provided with a reduced neck portion 1, having a rounded or slightly enlarged head 1^a, of general tapered or approximately conical form as shown, said head being provided with a plurality of port openings 1^b, arranged tangentially as shown most clearly in Fig. 4, of the drawings, and extending upwardly and outwardly as shown most clearly in Fig. 2, of the drawings.

The top or central portion of the nozzle head 1^a, is provided with a central opening having an upwardly inclined or tapered shoulder 1^c, to receive and form a seat for the similarly shaped tapered or truncated

head of the tubular irrigating member hereinafter referred to. The dilator is provided with an enlarged open base portion 1^a, provided with internal threads and is provided 5 at one side with a stem portion 1^c, forming a port communicating with the interior portion of the dilator body and adapted to be provided with a suitable hose 2, leading to a suitable vessel or appliance adapted to hold the irrigating or treating liquid.

As a means of providing a central irrigating port a tubular irrigating member 3, is provided, said tubular member 3, terminating at its top in the truncated head 15 3^a, adapted to extend into the opening at the top of the nozzle head 1^a, and to be seated within the inclined annular shoulder 1^c. The base of the tubular member 3, is provided with a base or bottom member 3^b, said base or bottom closure member 3^b, being provided with an annular flange to rest against the flange portion 1^a, of the dilator and being provided with internal threads adapted to be threaded within and to be 20 removed from the correspondingly threaded portion of the base 1^a.

It will be seen that when the member 3, with the base 3^b, are in assembled position that an annular chamber 4, is provided within the walls of the dilator in communication with the port or opening of the stem 1^c, and the ports 1^b, of the nozzle head, and it will also be observed that the tubular member 3, forms a central port or opening 3^c, leading through the center of the dilator and extending from the tip of the nozzle head to the face of the dilator body.

As a means of closing the port formed by the tubular member 3^c, and particularly 40 of forming the apex or nose of the tapered dilator head when it is desired to insert the latter a plug or filler member 5, is provided, said plug corresponding in length and dimensions to the opening in the tubular member 3, and being provided at its top with a tip 5^b, forming a continuation of the nozzle head and completing the tip or nose portion of the latter.

The base of the plug or filler 5, is preferably in the specific form of a disc head 5^b, adapted to rest beneath the bottom portion of the removable tubular irrigating member and to close the base of the port when the plug or filler is inserted.

55 The central port or opening 3^c, and the insert or plug 5, may be used as a means of applying healing salves or lotions to the top or nozzle head portion of the dilator and the surrounding walls or tissues as hereinbefore referred to and, if desired, the hose connection 2, may be utilized in creating a suction or partial vacuum within the annular chamber 4, and through the port openings 1^b, of the nozzle head in an obvious and 60 well understood manner.

Having thus described some of the embodiments of my invention, without having attempted to set forth all the forms in which it may be made or all the modes of its use, what I claim and desire to secure by Letters Patent, is,—

1. An irrigating rectal dilator, comprising a hollow dilator member, a hollow irrigating member extending therethrough and removable therefrom, and a removable plug provided with a head forming a part of said dilator member when seated.

15 2. In an irrigating rectal dilator having a central opening extending therethrough, a tubular irrigating member removable therein, a removable plug in said tubular member terminating in a head projecting above and forming the tip portion of said dilator, said tubular member being spaced from the walls of said dilator and conjointly therewith forming an annular chamber therein.

20 3. An irrigating rectal dilator, comprising a dilator of hollow formation including a nozzle head having a central opening and surrounding port openings, and a tubular irrigating member seated in and removable from said central opening and spaced from the walls of said dilator forming conjointly therewith an annular chamber therein communicating with said port openings.

25 4. An irrigating dilator of hollow formation including a nozzle head having a central opening and a series of tangentially arranged jet openings spaced from said central opening, and a tubular irrigating member removably seated in and communicating with said central opening and spaced from the walls of said dilator forming an annular chamber therein communicating with said jet openings whereby when said tubular irrigating member is seated an irrigating zone is formed between said jet openings and said central opening of said nozzle head.

105 5. In a rectal dilator and irrigator, a hollow dilator body having a nozzle head and a removable tubular irrigating member extending therethrough, and a removable plug adapted to fill said tubular member and having a head forming the tip of said nozzle head.

110 6. An irrigating rectal dilator, comprising a hollow irrigating member extending therethrough and removable therefrom and spaced from the walls thereof, and a removable plug extending through said hollow irrigating member and provided with a tapered head forming the tip of the dilator member.

115 7. An irrigating rectal dilator, comprising a hollow dilator member including a nozzle head having an annular series of jet openings, a tubular removable member extending therethrough forming an annular chamber within said dilator member and providing a central port communicating

with said nozzle head and forming an irrigating zone over the latter from said jet openings.

8. In a rectal dilator and irrigator, a hollow dilator body having a nozzle head, a tubular member extending therethrough, and a removable plug in said tubular member having a head forming the apex portion of said nozzle head.

10. An irrigating rectal dilator, comprising a dilator provided with an irrigating head including annular jet openings and a tubular removable irrigating member removably mounted in said dilator and spaced 15 from the walls thereof forming an annular chamber and providing a central port communicating with said irrigating head and jet openings.

10. An irrigating rectal dilator comprising a dilator provided with inlet and outlet ports and having an irrigating head communicating with the latter, and a tubular irrigating member removably mounted therein and spaced from the walls thereof 25 forming an annular chamber, said tubular irrigating member extending through and communicating with the irrigating head and base portions of said dilator.

11. In a rectal irrigating dilator, a hollow dilator body having a nozzle and a central opening, said dilator body being provided with an enlarged internally threaded open base portion and an inlet port, a tubular irrigating member removably mounted 35 in said hollow dilator body forming an annular liquid chamber therein and provided with a threaded base threaded in said open base portion of said dilator body, and a plug for closing said tubular irrigating member.

40 12. In a rectal irrigating dilator, a hollow dilator body having a tapered irrigat-

ing nozzle head having an opening provided with a tapered shoulder and an annular series of jet openings, said dilator body being provided with an enlarged open base 45 portion, and a removable tubular irrigating member forming an annular liquid chamber therein and provided with a base connected to said open base portion of said dilator, said tubular irrigating member having a 50 shouldered head seated within said undercut shoulder and communicating with said jet openings of said irrigating nozzle head.

13. In a rectal dilator and irrigator, the combination with a dilator body having a 55 nozzle head and tangentially arranged communicating ports at its top and a threaded base portion at its bottom; of an irrigating member extending axially through said dilator and spaced from the walls thereof 60 forming an annular chamber communicating with said ports, said irrigating member being provided with a threaded bottom removably mounted in the threaded base portion of said dilator. 65

14. An irrigating rectal dilator, comprising a dilator member having a threaded base portion and a nozzle head and a central opening, a tubular irrigating member extending into said opening and provided with 70 a threaded base threaded into the threaded base portion of said dilator member, and a removable plug filling said tubular irrigating member and adapted to close the same and form the tip of the dilator head when inserted and to be removed therefrom to form an opening in said irrigating member when used as an irrigator. 75

In testimony whereof I have affixed my signature.

ALBERT L. AUSTIN.
